(57) **CLAIM**

The ornamental design for a winch mounting platform with integral receiver hitch, as shown and described.

DESCRIPTION

FIG. 1 shows a rear perspective view of a winch mounting platform with integral receiver hitch of the present invention attached to a winch;

FIG. 2 shows a rear perspective view of the hitch winch mount as shown in FIG. 1 by itself and not attached to a winch;

FIG. 3 shows a front perspective view of a hitch winch mount as shown in FIG. 1 attached to a winch;

FIG. 4 shows a front perspective view of a hitch winch mount as shown in FIG. 2;

FIG. 5 shows a top view of the hitch winch mount as shown in FIG. 1 attached to a winch;

FIG. 6 shows a top view of the hitch winch mount as shown in FIG. 2;

FIG. 7 shows a rear view of the hitch winch mount as shown in FIG. 2;

FIG. 8 shows a front view of the hitch winch mount as shown in FIG. 2;

FIG. 9 shows a bottom view of the hitch winch mount as shown in FIG. 2;

FIG. 10 shows a left side view of the hitch winch mount as shown in FIG. 2;

FIG. 11 shows a right side view of the hitch winch mount as shown in FIG. 2;

FIG. 12 shows a bottom front perspective view of the hitch winch mount as shown in FIG. 2; and,

FIG. 13 shows a bottom rear perspective view of the hitch winch mount as shown in FIG. 2.

The broken line showing of the winch in FIGS. 1, 3, & 5 depict environment and forms no part of the claimed design. All other broken lines depict portions of the winch mounting platform with integral receiver hitch that form no part of the claimed design.
